FIG. 7.

INVENTOR

HERBERT O. ROSS,

by Ralph K. Laird ATTORNEY.

UNITED STATES PATENT OFFICE.

HERBERT O. ROSS, OF ST. LOUIS, MISSOURI.

INDEXED MAILING LIST

Application filed March 16, 1920. Serial No. 366,207.

To all whom it may concern:

Be it known that I, HERBERT O. Ross, a citizen of the United States, residing at the city of St. Louis, State of Missouri, have invented a certain new and useful Indexed Mailing List, of which the following is a specification, reference being had to the accompanying drawings, forming a part thereof.

10 This invention relates generally to indexes and, more particularly, to a certain new and useful indexed mailing-list.

15 The chief objects of my present invention are to provide a mailing or other list comprising a main or master list and one or more sub-lists giving specific data or information with respect to the names, businesses, or the like listed in the main or master list; to provide a list of the business

20 ter-list; to provide in a list or the kind stated a record-sheet having suitably captioned spaces and columns for embodying the main or master-list and with suitably captioned additional columns for embodying the sub-lists, and to also preferably provide such sheet with readily visibly distinguishable means for facilitating the reading of the several lists without error or confusion; to provide in a list or the like of the

30 kind stated a plurality of correspondingly columned individual record-sections or cards and a holder with which the several sections or cards are adapted for engagement in preferably overlapping arrangement to

35 collectively form a readily visible substantially continuous list or lists, the individual sections or cards being adapted for convenient placement in, or removal from, the holder, whereby revision of and correction in the list or lists may be made with facility

40 and economy; and to provide in a list or the like of the kind stated and in connection with said individual record-sections or cards and holder, an additional separate section or card bearing suitable captions for the 45 spaces and columns of the said individual record-sections or cards.

With the above and other objects in view, my invention resides in the novel features of form, construction, arrangement, and combination of parts hereinafter described and afterwards pointed out in the claims.

In the accompanying drawings,

Figure 1 is an elevational view of an indexed mailing-list embodying my invention; Figure 2 shows in perspective a fragment

55 Figure 2 shows in perspective a fragment

of the slotted holder for the individual record-sections or cards:

Figure 3 shows in perspective a fragment of the separate caption-bearing section or card;

Figure 4 shows in perspective a fragment of one of the individual record-sections or cards;

Figure 5 shows in enlarged perspective a fragment of the card-holder, a fragment of the caption-bearing section, and a fragment of the upper individual record-section, all associated together: 65

Figure 6 is an enlarged fragmental view of the holder and a pair of the individual sections, showing the manner of manipulating the overlapped section to permit removal from the holder of the overlapping section: and

Figure 7 is an enlarged elevational view 75 of a pair of the record-sections.

Referring now more in detail to the said drawings, which illustrate a practical embodiment of my invention and in which like reference characters indicate like parts throughout the several views, 1 indicates the card-holder, which is preferably of rectangular shape and of suitable sheet material, such as, for instance, relatively heavy paper-board or light sheet metal. This holder 1 is provided or formed adjacent its opposed or opposite vertical margins with rows or series of slots or openings 2 having preferably the angularly obtuse form seen especially in Figure 2, each slot 2 comprising a vertically disposed portion 3 and an upwardly and inwardly inclined portion 4, and as seen in Figure 1, the slots 2 are equidistantly spaced vertically and aligned horizontally in pairs.

5—5 indicate the separate individual record-sections or cards, each of which is constructed of suitable material and each of which is of a length to conveniently fit upon the holder 1 intermediate or between the portions 3 of its opposite marginal rows of slots 2, as seen in Figure 1. Each card or section 5 is formed at its ends with a pair of longitudinally extending tenons 6 each preferably reduced at its neck, as at 7, whereby the card or section 5 is adapted for facile engagement with the slots 2 of the holder 1. 100 105

8 indicates the caption-section or card, which is also of suitable material and of a length similarly, as shown, to fit between 110

the portions 3 of the opposite marginal rows of slots 2 of the holder, the card or section 8 being also formed at its ends for engagement with the holder with a single longitudinal tenon 9 likewise reduced at its neck, as at 10.

I may here state that, in assembling the several individual record-sections or cards 5 upon the holder 1, a particular section or card 5 is first placed in position, its pairs of tenons 6 being inserted into, and received by, two pairs of the obtuse slots 2 of the holder. The next upwardly adjacent section or card 5 is then placed in position, its lower portion inserted beneath, and thus overlapped by, the first card, the lower pair of tenons of the second card or section inserted into and received by the pair of slots 2 occupied by the upper pair of tenons of the first card, and the upper pair of tenons of the second card or section inserted into and received by the next upper pair of older-slots 2. Similarly the several individual record-sections or cards 5 may be fitted in overlapping and overlapped arrangement upon the holder 1 and as so disposed upon the holder 1 provide substantially a visibly continuous, though sectional, sheet, the caption-section 8 being suitably fitted at its tenons 9 into engagement with the uppermost pair of slots 2 of the holder 1, as shown. With the several sections 5 and 8 so mounted or arranged upon and engaging the holder 1, it will be seen that the central edge portions of each overlapped section fit over the oblique portions 4 of the slots 2 occupied by the upper pair of tenons of the next adjacent overlapping section, such slots 2 being thereby restricted in dimensions to prevent withdrawal of the upper tenons of the overlapping, though upon the holder 1 lower, section and such lower, overlapping section being thus releasably locked against accidental removal or displacement. By manual manipulation, however, of the upper, overlapped section to draw its edge-portions from over the portions 4 of said slots 2, the lower, overlapping sections may be conveniently removed for any desired purposes and again reinserted in position, or substitution of a new section therefor readily made, the upper, overlapped section on being released again locking the lower section from removal as described.

The several individual record-sections or cards 5, as well as also the caption-section 8, are correspondingly provided along the right-hand portions thereof with columns 11 formed by suitably spaced lines 12, these several columns, when the cards or sections 5 and 8 are fitted and arranged upon the holder 1 as described, being vertically substantially continuous, as seen especially in Figure 1. The major portions 13 of the

several sections or cards 5 to the left of the several columns 11 provide a convenient space or column for receiving the names of individuals, corporations, businesses, or the like being listed, columns 11 of the several individual sections 5 being conveniently adapted to receive any specific data or information with respect to the concerns, businesses, or the like appearing and listed in the main column or space 13. To identify or indicate to the user of the list the compiled data or information of the several columns 11, of the several sections or cards 5, the corresponding columns 11 of the caption-section or card 8 have printed or otherwise preferably permanently affixed therein suitable appropriate headings or captions, as shown, while on the corresponding body or space 13 of the caption-section 8 appears, as seen in Figure 1, a suitable or appropriate heading or caption for the matter appearing in the column or space 13 of the several sections or cards 5. Obviously such headings or captions may vary; I have arbitrarily selected for purposes of this specification captions or headings applicable particularly for an index for a mailing-list, the spaces 13 of the several individual record-sections or cards 5 containing the listed names and addresses, by hand-writing or otherwise, of persons or concerns to whom matter, such, for instance, as advertising matter or literature, may be directed, and such column being appropriately identified on the caption-section 8 by the heading "Name and address", and the spaces in the columns 11 aligned with any particular name containing data or information, such as commercial rating, lines of goods or merchandise carried, seasons, customers, and so on, suitably or appropriately captioned by the section 8, relating to the listed persons or concerns. In the example shown, for instance, I have illustrated a mailing-list, in which the uppermost or top individual record-section 5 bears in its space 13 the name and address of "John Brown Mfg. Co., St. Louis, Mo., 123 Olive St." In the column 11 captioned "Rating thousand", there is written the number "10". In the column 11 captioned "Class A", there appears an "x". And in the column 11 captioned "Station'y", there also appears an "x". Thus this card at once gives or conveys to the user of the list the information that the John Brown Mfg. Co. is financially rated at \$10,000.00, commercially is of Class A credit, and handles and is interested in stationery. Certain of the other individual record or listing sections 5 may, by an "x" or an "s" or other symbol or the like, show that the particular concern listed on any particular section or card 5 handles various merchandise and various "lines" of goods, that sales in one or more "lines" have been made to him, or other pertinent

- information. Thus I provide in a mailing-list the main or master-list, comprising the names and addresses of the businesses or concerns listed in the column 13, and one 5 or more supplemental sub-lists provided by the columns 11, which, as described, supply pertinent and valuable data or specific information relating to the persons or concerns comprised in the main or master-list.
- 10 The master-list so consolidates into one main list all of the possible listings, and the accompanying columns or sub-lists 11 give all of the advantages of a number of small special classification lists. The columns 11 15 afford an inexpensive way of carrying or compiling detail information about each name comprised in the master-list and thus offer substantially an unlimited variety of special notations or classifications, such as 20 a memorandum or list for seasonable follow-up, grading of prospects, lines of merchandise carried by customer, lines of merchandise sold to customer, lines of merchandise yet to be sold to customer where 25 customer has only purchased from one or two departments of a concern, and, in effect, provide an automatic chart of customers, prospects, or memoranda, showing their relation to each other. The columns 30 11 further provide means for an unlimited number of sub-lists of the main list, thus facilitating the adding or locating of any special class within the main list, and also for eliminating duplicate names between 35 a number of small classifications within the main list which may overlap; for instance, if a given or particular name be classified or listed in each of a number of classes, the column rules permit the name to be carried 40 in each list or classification, yet at the same time eliminate consideration of duplicate names which would otherwise appear in the lists if the same were separated. Each of the individual record-sections or cards 5 45 being independently removable from the holder 1 as before described, an unlimited revision of the main or master list may be readily made to, for instance, clear items or names off the main list, add new names or 50 items, correct or revise present names or items; and it will be clear that individual handling of the sections or cards 5 is entirely obviated and time and labor thus economized in the use of the list, since the 55 same are readily visible at all times substantially as a continuous sheet. If desired, the several individual record-sections may be of distinguishable characteristics to denote or indicate, for instance, time of listing—thus one section 5 may be of a certain color, as shown to denote a 1919 entry, another section 5 may be of a different color, also as shown, to denote a 1918 entry, and so on throughout the several individual sections, a key to the information conveyed by 60 65 70 75 80 85 90 95 100 105 110 115 120 125 130
- the various colors or characteristics of the sections 5 being, of course, in the possession of the user of the index or lists. And further to facilitate the reading of the several columns 11 without error or confusion, the several column-forming lines 12 may be distinguished in color or otherwise one from the other, as shown.
- This indexing or listing may be readily adapted by a change of the caption-card 8 to an infinite variety of uses, as will be evident; and it will be obvious that the individual record-sections 5 may be more or less extended downwardly in length to provide a suitable space for pertinent remarks, book-keeping entries, and the like, having to do with the particular person or concern whose name appears listed upon the particular section, a reading of which information may be readily had by either a removal of the particular card or a springing of its overlapping card or even of the holder sufficiently to permit the covered or overlapped portion of the particular section to be seen.
- The several record-sections 5 and their holder 1, it may be added, are convenient also as a memorandum system. The sections 5 may be placed in order of importance on the holder, and as the different items are taken off the base card or holder, new items take their place; or if an item becomes of greater or less importance, such section may be shifted up or down on the holder to a position that clearly indicates or shows the degree of its importance.
- My new index may be readily applied to many uses other than those herein specifically mentioned, and it is to be understood that changes in the form, construction, arrangement, and combination of the several parts of my new index may be made and substituted for those herein shown and described without departing from the nature and principle of my invention.
- Having thus described my invention, what I claim and desire to secure by Letters Patent is:
1. A record list including, in combination, a holder provided with a pair of horizontally-aligned slots, a separate record-section, and flaring outwardly-projecting tenons at the opposite ends of said section adapted to removably fit in said slots for separably supporting the section upon the holder.
  2. A record list including, in combination, a holder provided with a pair of horizontally-aligned oppositely-disposed obtuse-angle slots, a separate record-section, and flaring outwardly-projecting tenons at the opposite ends of said section adapted to removably fit in said slots for separably supporting the section upon the holder.
  3. A record-list including, in combination, a holder provided with a pair of horizontally-aligned slots, a pair of individual rec-

ord-sections, and outwardly-projecting flaring tenons on each of said sections adapted to removably fit in overlying relation in said slots for separately supporting the sections 5 upon the holder.

4. A record list including, in combination, a holder provided with spaced rows of horizontally aligned slots, a plurality of separate individual record sections, and outwardly-projecting tenons upon each of said sections adapted to removably fit in overlying relation in opposed pairs of said slots 10 for separably supporting said sections in an edgewise overlapping series upon the holder.

15 5. A record-list including, in combination, a holder provided with pairs of horizontally aligned slots having one end inclined inwardly at an obtuse angle, a pair of individual record-sections, and flaring outwardly projecting tenons on each of said sections adapted to removably fit in said slots, one section edgewise underlying the other section 20 for locking the overlapping section against removal.

25 6. A record-list including, in combination, a holder provided with pairs of horizontally aligned slots having one end inclined inwardly at an obtuse angle, a pair of individual record-sections, and flaring outwardly projecting tenons on each of said sections adapted to removably fit in said slots, the one section restricting the slots occupied by the tenons of the other section for locking 30 the same against removal.

35 7. A record-list including, in combination, a holder provided with pairs of horizontally aligned slots having one end inclined inwardly at an obtuse angle, a record-section provided with longitudinal flaring tenons adapted to removably fit in certain 40 of said slots for detachably supporting said section upon the holder, and a second record-section also provided with longitudinal flaring tenons adapted to removably fit in slots 45 occupied by tenons of the first section, the one section restricting said latter slots for locking the tenons of the other section against removal.

50 8. A record-list including, in combination, a holder provided with pairs of horizontally aligned obtuse-angle slots, a record-section provided with longitudinal flaring tenons adapted to removably fit in certain 55 of said slots for detachably supporting said section upon the holder, and a second record-section also provided with longitudinal flaring tenons adapted to removably fit in the slots occupied by tenons of the first section, the one section overlying portions of 60 and restricting said latter slots for locking the tenons of the other section against removal.

65 9. In a record-list or the like, the combination with a holder provided with spaced rows of horizontally aligned obtuse angle

slots, of a record-section provided with pairs of longitudinal tenons of reduced width at their neck, said tenons being adapted to fit in certain of said slots to support the section upon the holder, and a second record-section 70 also provided with longitudinal tenons adapted to fit in some of the slots occupied by tenons of the first section to support the second section upon the holder, the second section being adapted to overlie portions of and restrict the slots occupied by tenons of both the first and second sections and thereby lock the first section against removal.

10. In a record-list or the like, the combination with a holder provided with spaced rows of horizontally aligned slots, each slot comprising a vertically disposed portion and a communicating obliquely disposed portion, of a record-section provided with a pair of longitudinal tenons of reduced width at their neck, said tenons being adapted to fit in certain of said slots to support the section upon the holder, and the body of each tenon having a width greater than the width of the vertically disposed portion of its said slot, and a second record section also provided with tenons adapted to fit in certain of said slots to support the second section upon the holder, the second section being 95 adapted to overlie the obliquely disposed portions of the slots occupied by the tenons of the first section and thereby lock the first section against removal.

11. A mailing-list including a holder-section, in combination with a plurality of individual separate record-sections, each record-section having a plurality of surface columns formed by spaced transverse lines for the compilation of a main list and of one or more sub-lists of the main list, the holder and each respective record-section being adapted for separable interengagement and said record-sections when in interengagement with the holder-section being disposed in an edgewise overlapping series over and upon the holder-section, the columns of the record-sections then aligning and the several record-sections then forming substantially a single continuous sheet.

12. A mailing-list including a holder-section, in combination with a plurality of individual separate record-sections, each record-section having a plurality of surface columns formed by spaced transverse lines for the compilation of a main list and of one or more sub-lists of the main list, the holder and each respective record-section being adapted for separable interengagement and said record-sections when in interengagement with the holder-section being disposed in an edgewise overlapping series over and upon the holder-section, the columns of the record-sections then aligning and the several record-sections then forming substan- 130

tially a single continuous sheet, and designating captions upon the holder-section aligning with and for the entries of the respective columns of the attached record-sections.

13. A mailing-list including a holder-section, in combination with a separate caption-section, a plurality of individual separate record-sections, each record section 10 having a plurality of surface columns formed by spaced transverse lines for the compilation of a main list and of one or more sub-lists of the main list, the holder-section and the caption-section and the 15 holder-section and each respective record-

section being adapted for separable inter-engagement and said caption and record-sections when in interengagement with the holder-section being disposed in an edge-wise overlapping series over and upon the 20 holder-section, the columns of the record-sections then aligning, the several record-sections then forming substantially a single continuous sheet, and the caption-section bearing designating-captions for and then 25 aligning with the respective columns of the record-sections.

In testimony whereof, I have signed my name to this specification.

HERBERT O. ROSS.
